(57) **CLAIM**

The ornamental design for safety footwear as shown and described.

DESCRIPTION

FIG. 1.1 is a right side perspective view of the footwear, according to my design.

FIG. 1.2 is rear left side perspective view thereof.

FIG. 1.3 is front right side perspective view thereof.

FIG. 1.4 is a rear right side perspective view thereof.

FIG. 1.5 is a right side elevation view thereof.

FIG. 1.6 is a left side elevation view thereof.

FIG. 1.7 is a front elevation view thereof.

FIG. 1.8 is a rear elevation view thereof.

FIG. 1.9 is a top plan view thereof.

FIG. 1.10 is a bottom plan view thereof.

The broken lines in Figures 1.1-1.6 and 1.10 indicate surface indicia that form no part of the claimed design.

1 Claim, 10 Drawing Sheets
